UNITED STATES PATENT OFFICE

ALPHONSE HAAS, OF SAN BERNARDINO, CALIFORNIA

CIGAR OR CIGARETTE ASH PROTECTOR

Application filed February 26, 1929. Serial No. 342,903.

My invention is a cigar or cigarette ash protector adapted to catch the ash falling from the end of a cigar or cigarette.

An object of my invention is a device which may be attached to a cigar or cigarette and catch the ash falling from the end of such cigar or cigarette and in this connection a further object of my invention is having a protecting guard which is open at the top allowing ready lighting of the cigar or cigarette and having a gauze structure forming the card proper. This gauze structure retains the ash until the user desires to empty the guard.

Another object of my invention is constructing the device with clamping jaws preferably under a spring pressure to readily grip a cigar or cigarette and adapted for cigars and cigarettes of different diameters.

By this construction as the cigar or cigarette is consumed it may be thrust forth into the protector and thus the cigar or cigarette may be smoked completely.

Another detailed object of my invention is making the device in a plurality of discon- 25 nectable sections, whereby the user may readily disassemble the device for cleaning or the like and in this connection I prefer- ably assemble the parts with a bayonet type 30 of joint and attach the clamping jaws on a central removable section.

My invention is illustrated in the accom- 35 panying drawings, in which Fig. 1 is a plan of my device showing a cigar retained therein;

Fig. 2 is a transverse section on the line 2—2 of Fig. 1 in the direction of the arrows;

Fig. 3 is a perspective view of the several 40 elements entering into the construction of my protector, these being shown somewhat in alinement to indicate the manner of assembly;

Fig. 4 is a side elevation of a cigarette 45 ash protector.

In constructing my invention I utilize a 50 protecting guard 11 which is formed preferably of wire gauze and has a bead 12 surrounding the open top section 13. In this bead there is a stiffening wire 14. The main

body of the device may be somewhat cylindrical and preferably has a rounded end 15. The guard is secured to a guard holding ring 16, the connection being preferably by rivets 17, grommets or the like and extending internally of such ring there are projecting pins 18, these pins being illustrated as diametrically opposite one to the other. A central ring 19 is formed of suitable material and has two bayonet slots 20 to engage with the pins 18 and retain the ring 19 firmly held inside of the ring 16. This ring 19 has two L-shaped slots 21 separated by a tongue 22. A pin 23 is centrally positioned in the cut-out section 24 of the ring. There is a second pair of bayonet type slots 25 in the opposite edge of the ring from the bayonet slots 20.

Clamping jaws 26 are formed of an upper jaw member 27 having a relatively long handle 28 and a lower jaw 29. These jaws connect together by a coil spring 30, such spring being twisted to form an eye 31 which may fit over the pin 23. The free ends 32 of each of the jaws fit in the circumferential portion of the L-shaped slots 21, the tongue 22 retaining the tips 32 of the jaws.

An outside ring 33 is formed with a cylindrical section 34 and an inwardly extending flange 35. A pair of pins 36 are attached to the cylindrical section 34 on the inside. These pins engage in the bayonet slots 25 and thus clamp the device together and hold the clamping jaws in position.

My ash protector is as follows: The ring 39 is connected to the ring 16 having the trough-shaped guard by inter-engaging the bayonet slots 20 and the pins 18, the rings being given a turn to lock the bayonet joint. The clamp 26 is secured in place by passing the pin 23 through the twist spring 30. The ends 32 of the jaws pass on opposite sides of the tongue 22 and fit in the circumferential portion of the L-shaped slots 21. The outside ring 33 is then secured in place, the pins 36 cooperating with the bayonet slots 25. The device is thus compactly held in position and yet may readily be disassembled when desired.

The protector for cigarette is of the same

design but smaller as the protector for cigars. By my construction the cigar is readily grasped by the jaws and thus the protector is held in proper position on the 5 cigar or cigarette. The open top in the trough-shaped guard allows ready igniting of the cigar or cigarette and as this is consumed in smoking it may be thrust forth between the jaws and by such action the cigar 10 or cigarette may be smoked until practically all consumed. The ash collected in the trough-shaped guard 11 may then be removed by inverting the device.

My protector may readily be placed on a 15 table or other furniture without fear of damaging such table or furniture and is held in the proper position by the handles of the jaws.

Various changes may be made in the principles of my invention without departing 20 from the spirit thereof as set forth in the description, drawings and claims.

I claim:

1. An ash protector comprising in combination a first ring, a second ring detachably connected thereto, a clamp having a pair of jaws mounted in the second ring and a hollow structure attached to the first ring adapted to receive the ash of a cigar or 30 cigarette secured in the jaws extending longitudinally through the two rings.

2. An ash protector comprising in combination a first ring, a second ring having a bayonet slot and pin connection with the 35 first ring, a pair of jaws pivotally mounted on the second ring, and a hollow structure connected to the first ring adapted to receive ash from a cigar or cigarette secured in the jaws extending longitudinally 40 through the rings.

3. An ash protector comprising in combination a ring having a cut-out section with a pin in said section, a pair of L-shaped slots, a clamp having a pair of jaws pivotally mounted on the pin, the ends of the 45 jaws fitting in the L-shaped slots, a structure having a trough-like foraminous body secured to the ring, the clamp being adapted to retain a cigar or cigarette extending longitudinally through the ring.

4. An ash protector comprising in combination a first ring having a trough-shaped guard connected thereto, a second ring having a detachable connection to the first ring 55 and having a pin extending longitudinally and slots opposite the pin, a clamp having a pair of jaws pivotally mounted on the pin, the ends of the jaws fitting in the said slots, and a third ring fitting on the outside of 60 the clamp on the said second ring.

5. An ash protector comprising in combination a first ring having a trough-shaped guard secured thereto, a second ring having a detachable connection to the first ring and 65 having a cut-out section with a pin extend-

ing longitudinally of the second ring, said second ring having L-shaped slots spaced apart by a tongue, a clamp having a pair of jaws pivotally mounted on the said pin, the ends of the jaws fitting in the said L-shaped slots, and a third ring secured to the second ring on the outside of the said clamp. 70

In testimony whereof I have signed my name to this specification.

ALPHONSE HAAS.
